United States Patent Office

Des. 232,228

Patented July 30, 1974

232,228

AWNING

George W. Wells, 75 Locust Ave.,
Peekskill, N.Y. 10566

Filed July 14, 1972, Ser. No. 271,806

Term of patent 14 years

Int. Cl. D25—02

U.S. Cl. D21—6 B

FIG. 1 is a front, bottom and left side perspective view of an awning showing my new design;

FIG. 2 is a front elevational view thereof;

FIG. 3 is a right side elevational view thereof.

I claim:

The ornamental design for an awning, as shown.
